US00D618708S

(12) **United States Design Patent**
Quirke et al.

(10) **Patent No.:** **US D618,708 S**
(45) **Date of Patent:** ** *Jun. 29, 2010

(54) **HARVESTING HEAD**

(75) Inventors: **Peter Quirke**, Tokoroa (NZ); **Alex J. Stevenson**, Papamoa (NZ); **Justyn P. Smythe**, Cambridge (NZ)

(73) Assignee: **Waratah NZ Limited**, Tokoroa (NZ)

(*) Notice: This patent is subject to a terminal disclaimer.

(**) Term: **14 Years**

(21) Appl. No.: **29/338,474**

(22) Filed: **Jun. 12, 2009**

(51) **LOC (9) Cl.** **15-03**

(52) **U.S. Cl.** **D15/28; D15/10**

(58) **Field of Classification Search** D15/28, D15/10; 144/4.1, 343, 24.13, 338, 357, 3.1, 144/208.1, 34.1

See application file for complete search history.
